MIXING TOOL

Earl S. Tupper, Upton, Mass.

Application January 24, 1955, Serial No. 34,175

Term of patent 14 years

(Cl. D44—1)

Fig. 1

Fig. 2

Fig. 3

Fig. 4

Fig. 5

Figure 1 is a perspective view of a mixing tool embodying my new design;

Figure 2 is a front view thereof in elevation;

Figure 3 is a side view thereof in elevation;

Figure 4 is a sectional view across the line 4—4 of Figure 2; and

Figure 5 is a sectional view across the line 5—5 of Figure 2.

I claim:

The ornamental design for a mixing tool, as shown.
